UNITED STATES PATENT OFFICE.

GEORGE H. WARREN AND SAMUEL FONTAINE, OF MINNEAPOLIS,
MINNESOTA.

STORAGE-BIN.

No. 827,589.

Specification of Letters Patent.

Patented July 31, 1906.

Application filed September 14, 1904. Serial No. 224,418.

To all whom it may concern:

Be it known that we, GEORGE H. WARREN and SAMUEL FONTAINE, citizens of the United States, and residents of Minneapolis, in the 5 county of Hennepin and State of Minnesota, have invented a new and Improved Storage-Bin, of which the following is a full, clear, and exact description.

Our invention relates to the construction 10 of storage-bins, especially those used for the storage of grain and similar materials which must be kept free from moisture.

The principal object of our invention is to provide for keeping the materials stored both 15 moisture and fire proof, and certain other objects of our invention will appear in the course of the subjoined description.

Reference is to be had to the accompanying drawings, forming a part of this specification, in which similar characters of reference indicate corresponding parts in all the figures.

Figure 1 is a side elevation of a grain-bin constructed in accordance with one form of our invention, showing a portion in section.

Fig. 2 is a sectional view thereof on the line 2 2 of Fig. 1. Fig. 3 is a sectional view similar to the part shown in Fig. 1 in section and on an enlarged scale. Fig. 4 is a sectional view of a fastening device on the line 4 4 of

30 Fig. 5. Fig. 5 is a plan view of the same. Fig. 6 is a sectional view similar to Fig. 3 of a modification. Fig. 7 is a horizontal sectional view of a circular form of bin, showing certain modifications and taken on two sec-

35 tional planes represented in Fig. 7^a by the lines 6 6 and 6^a 6^a. Fig. 7^a is a sectional view on the line 7^a 7^a of Fig. 7. Fig. 8 is a perspective view of a detail. Fig. 9 is a plan view, partly in section, showing a modifica-

40 tion which may be used with a square-cornered bin. Fig. 10 is a sectional view on the line 10 10 of Fig. 9, and Fig. 11 is a perspective view of a particular form of plastic block that may be employed in all modifications.

45 Referring especially to Figs. 1, 2, and 3, 1 designates the base of the structure, which may be composed of any suitable material, such as stone, brick, cement, &c. In the 50 present instance the base is shown substantially square in form with rounded corners; but other forms may be employed without

departing from the spirit of our invention. On top of the base portion is arranged the bottom of the tank 2, which may be of asphalt, cement, or any like fireproof and damp-proof material. Mounted upon this bottom portion 2 is the bin or tank proper, which comprises the following parts: Its outer wall 3 may be of any material—such as 55 stone, brick, or metal—and it is preferably provided with a top portion or cap 4 of metal. Within the outer casing 3 is arranged an inner shell spaced from the outer wall, so as to provide an air-space 5. Within this structure are arranged a plurality of receptacles *a*, which preferably extend from the bottom to the top of the casing 3 and are connected thereto by means of tie-rods (represented at 6) and secured to each other by tie-rods 6^a. 70 These receptacles *a* are preferably built up of a series of blocks or bricks of concrete, cement, or other suitable material. These bricks may be arranged in various ways, as the several figures indicate. 75

In the form illustrated in Fig. 3 two kinds of bricks are employed, one (indicated at 7) being provided with channels or grooves 8, which are adapted to register with each other, so that a circular channel is formed in the 80 wall when the bricks are cemented or laid in position. The channels are filled with cement or like binding material, as indicated at 9, and embedded in the cement are one or more strengthening - bars 10, which extend entirely around the wall of the inner shell *a* and assist in securely holding and binding the bricks and strengthening the shell. Between every two rows of channeled bricks or blocks is arranged a layer of ordinary bricks 11, 90 which may be held in the structure by binding-mortar in the ordinary manner. The blocks 7 and 11 are preferably provided with rods 7^a and 11^a, respectively, embedded in the material and extending around the casings of 95 the inner shells. These bars are embedded in the blocks for the purpose of preventing them from cracking while drying.

In the form shown in Fig. 6 the tie-rods 6 are replaced by plastic blocks 6^b, constituting a portion of the outer wall as well as of the inner walls *a*. These blocks will serve to tie the two walls together, and they are preferably placed in different positions, as indi-

cated in Fig. 6, so as to add to the strength of the structure. Strengthening-bars similar to those marked 10 in Fig. 3 are shown at 10^a.

If desired, the base portion 2 may be provided with strengthening-bars 2^a, as shown in Fig. 6. Figs. 4 and 5 represent another form of plastic tie-rod 6^e having a metal strengthening-core 6^f.

In the construction shown in Figs. 7 and 7^a the external and internal walls are concentric and are provided with vertical apertures 5^b for the circulation of air. The space between them is filled by plastic blocks 14, and dovetailed or L-shaped grooves 15 are provided for the purpose of holding the ends of the strengthening-bars 6^e, which are of somewhat different form from those illustrated in the other figures mentioned. Certain of the blocks between the two walls 11^b, as shown at 16, are provided with wires or cables 17, extending around the circumference of the bin, while others are provided with circular bars 18, as shown at the bottom of Fig. 7^a.

In Figs. 9 and 10 we have illustrated a construction which is convenient to use in square-cornered bins, which comprises tie-rods 6^d and channel-irons 12, arranged in pairs separated by the tie-rods and held in position by means of the bolts 13. In this construction certain of the plastic blocks, as indicated at 7^b, are provided with plastic fillings 7^c, surrounding channel-irons 10^b and 10^c.

In Fig. 11 is illustrated a form of building-block 7^e which we prefer to use in this construction. It is provided with channels 8 and 8^a on one side and with a channel 8^b on the other. These channels are preferably molded with a strip across their outer ends, which may be easily fractured after they are baked, so as to produce a block such as that shown in Fig. 11. These blocks are also preferably provided with air-passages 8^c.

Our improved grain-bin is, as has been shown, provided with means for the circulation of air, for preventing the admission of moisture, and for reducing the possibility of a destruction of its contents by fire. It will therefore be very durable and very efficient for the purpose intended.

From the several modifications shown it will be obvious that the invention is not limited

to the exact constructions described, but may include all such as fall within the scope of the 55 appended claims.

Having thus described our invention, we claim as new and desire to secure by Letters Patent—

1. A storage-bin comprising an outer 60 casing, inner casings spaced from the outer casing, tie-braces connecting the walls of the said casings, said tie-braces comprising channel-irons secured together, and bars secured to said channel-irons. 65

2. A storage-bin comprising a casing constructed of fireproof blocks each having a plurality of channels upon one face extending toward the opposite face, a channel upon the opposite face extending toward the first-mentioned face between the other channels, and air-passages located near one face and adjacent to the inner end of one of said channels. 70

3. A storage-bin, comprising a casing constructed of blocks each having a channel upon one face extending toward the opposite face, a parallel channel from the opposite face extending toward the first-mentioned face, and air-passages located parallel with 80 the channels near one face and adjacent to the inner end of one of the channels. 75

4. A bin comprising a casing constructed of blocks each having longitudinal air-channels separated from each other and located 85 on one side, a channel located on the same side and opening outwardly at the edge of the block, in alinement with said air-channels, and a channel on the opposite side of the block opening outwardly on the opposite 90 edge extending longitudinally through the block from end to end, and transversely through the block from one edge nearly to the other.

In testimony whereof we have signed our 95 names to this specification in the presence of two subscribing witnesses.
